UNITED STATES PATENT OFFICE.

GEORGE C. KINDT, OF JERSEY CITY, NEW JERSEY, ASSIGNOR TO GEO. BORGFELDT & CO., OF NEW YORK, N. Y., A CORPORATION OF NEW JERSEY.

DESIGN FOR A SPUN-METAL VESSEL.

49,777.

Specification for Design.

Patented Oct. 17, 1916.

Application filed January 19, 1916. Serial No. 73,081. Term of patent 3½ years.

To all whom it may concern:

Be it known that I, GEORGE C. KINDT, a citizen of the United States, residing in Jersey City, county of Hudson, and State of New Jersey, have invented a new, original, and ornamental Design for a Spun-Metal Vessel, of which the following is a specification, reference being had to the accompanying drawing, forming a part thereof, and in which the figure is an elevation of

a spun copper vessel showing my new design.

I claim—

The ornamental design for a spun metal vessel as shown.

GEORGE C. KINDT.

Witnesses:

GEO. J. PFEIFFER,
L. BULLINGER.
